J. ZITZERMAN

SOUND BOX AND TONE ARM

Filed June 30, 1923

Patented Oct. 27, 1925.

1,559,514

UNITED STATES PATENT OFFICE.

JACOB ZITZERMAN, OF BROOKLYN, NEW YORK.

SOUND BOX AND TONE ARM.

Application filed June 30, 1923. Serial No. 648,704.

To all whom it may concern:

Be it known that I, JACOB ZITZERMAN, a citizen of Russia, and a resident of the city of New York, borough of Brooklyn, in the 5 county of Kings and State of New York, have invented a new and Improved Sound Box and Tone Arm, of which the following is a full, clear, and exact description.

This invention relates to sound reproducing machines and has particularly reference to an improvement in the sound box and tone arm thereof.

Some of the outstanding objects of the present invention are to provide a sound box 15 which completely houses and protects the diaphragm; which simplifies the needle bar mounting; and which aims to increase the quality of the tone of the machine.

The invention furthermore contemplates 20 an improvement in the tone arm mounting whereby the tone arm is maintained in a steady position and more effectively supports the outer free end with which the sound box is associated.

As a still further object the invention contemplates a sound box and tone arm which is comparatively simple in its construction, inexpensive to manufacture, and which is 25 thoroughly reliable and highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the 35 full extent indicated by the general meaning 40 of the terms in which the claims are expressed.

In the drawings—

Figure 1 is a fragmentary sectional view 45 through a machine equipped with a tone arm and sound box constructed in accordance with the invention.

Fig. 2 is a sectional view through the sound box taken approximately on the line indicated at 2—2 in Fig. 1.

Fig. 3 is a fragmentary rear view of the tone arm with parts broken away and shown in section to disclose the underlying structure.

Referring to the drawings by characters 55 of reference 10 designates the bed of the machine cabinet over which the turntable 11 is

mounted for rotation and which bed or base is apertured as at 12 to receive therethrough the depending tubular boss 13 of the tone arm mounting base 14. The base 14 is provided with an upstanding collar 15 having a substantially horseshoe shaped bracket 16 into which the downturned rear end 17 of the tone arm 18 projects, the said lower extremity 19 of the downturned end 17 being 60 received in the upper enlarged bore of the cover 15. Immediately below the extremity 19 of the tone arm a step bearing 20 is arranged in the reduced bore of the collar 15 and receives a pintle 21 at the lower end of the vertical shaft section 22 which extends axially through the downturned end 17 of the tone arm and protrudes therethrough, said shaft having a bearing socket 23 in its upper end which receives the downwardly 65 projecting bearing pin 24 threaded through the bight of the horseshoe shaped bracket 16. Under this arrangement the tone arm is more steadily mounted for horizontal swinging movements. The outer end of the tone 70 arm has swiveled therein an arcuately turnable end section 25 with which the sound box designated generally by the character 26 is associated. The sound box consists of a pair of mating semi-spherical sections 27 75 and 28, the former being provided with a bossed outlet 29 over which the end section 25 of the tone arm is frictionally and telescopically engaged. Within the section 27 an annular enlargement providing a seat 30 80 is formed and from its outer open side an annular flange 31 extends. The opposite section 28 is provided with a pair of spaced concentric inner and outer annular flanges 32 and 33 which define therebetween an annular groove 34 for receiving therein the flange 31 of the section 27 when the sections 85 are in mated relation. The diaphragm 35 provided with a yieldable periphery 36 is adapted to be clamped between the inner 90 end of the inner tongue 32 and the seat or shoulder 30 when the sections are in mated relation and the sections are retained against relative separation by countersunk screws 37 which pass through the flanges 31, 32 and 33. At its lower end the sound box section 27 is provided with an axially projecting circular collar 38 and the flanges 31, 32 and 33 are apertured in alignment with the collar to allow for the passage therethrough of the stylus bar 39, the enlarged outer end 40 of which is provided with an end socket 41 100 105 110

in which the stylus 42 is received and retained by a screw 43. The stylus bar is pivoted to the collar by means of cone bearings 44 and is further provided with a hollow or space 45 within the same which tends to render the sound reproduction mellower and to eliminate scratching vibrations of the diaphragm. The outer section 28 is provided with a plurality of openings 46 and 10 with a central outwardly projecting manipulating handle 47 for lifting and turning the sound box and tone arm section 25.

Under this arrangement it will be noted that the diaphragm is thoroughly covered and protected against breakage while the same may be readily uncovered and removed for the purpose of repairs by simply removing the screws 37 and the outer section 28.

I claim:

20 1. A sound box for sound reproducing machines comprising a pair of mating semi-spherical sections one of said sections having at its open edge internal and external annular rabbets, the internal rabbet being of 25 greater depth than the external rabbet and defining an annular seat at its inner end, the other section having concentric inner and outer spaced flanges at its open edge, the inner flange being of greater width than the 30 outer flange and designed to be received within the internal rabbet of the other section to coact at its outer end with the seat to clamp a diaphragm thereagainst, the outer flange fitting within the outer rabbet and defining together with the inner flange a 35 groove for the reception of the projecting portion of the other section, and fastening elements extending radially through the outer and inner flanges of one of the sections and the projecting portion of the other section.

40 2. A sound box for sound reproducing machines comprising a pair of mating semi-spherical sections one of said sections having at its open edge internal and external annular rabbets, the internal rabbet being of 45 greater depth than the external rabbet and defining an annular seat at its inner end,

the other section having concentric inner and outer spaced flanges at its open edge, 50 the inner flange being of greater width than the outer flange and designed to be received within the internal rabbet of the other section to coact at its outer end with the seat to clamp a diaphragm thereagainst, the outer flange fitting within the outer rabbet and defining together with the inner flange a groove for the reception of the projecting portion of the other section, and fastening elements extending radially through the 55 outer and inner flange of one of the sections and the projecting portion of the other section, the said first mentioned section having an axially projecting radially apertured collar and the flanges of the said second section and open edge at the first section having alined notches for receiving therethrough the stylus bar of the diaphragm.

3. A sound box for sound reproducing machines comprising a pair of mating semi-spherical sections, one of said sections having an internal annular rib defining a seat at the outer corner of the free edge being rabbeted to provide an annular outwardly projecting flange, spaced concentric inner and outer flanges formed at the outer edge of the other section defining therebetween an annular groove within which the annular flange of the first section is received, the inner flange of the second section extending within the open end of the first section and adapted to coact with the internal seat for clamping therebetween a diaphragm, the outer flange of the second section extending within the rabbeted outer corner of the first section, a collar projecting from the edge of the first section, the said flange of the first section and flanges of the second section having alined openings disposed in registry with the collar for receiving therethrough the stylus bar of the diaphragm and means extending through the overlapping flanges of said sections for removably connecting the sections together.

JACOB ZITZERMAN.
